UNITED STATES PATENT OFFICE.

JAMES MONROE HEWLETT, OF LAWRENCE, NEW YORK.

PARTITION WALL.

Application filed June 28, 1926. Serial No. 118,884.

The present invention relates to a method of building walls, particularly partition walls, by the use of blocks which are laid up without mortar, and preferably are subsequently plastered. This invention is particularly applicable to blocks made of light fibrous material but can also be used with ordinary gypsum blocks or blocks made of tile.

10 In accordance with this invention, I utilize a form of metal clip which is forced into place between the blocks and holds them in place while the wall is being built and then is locked to the blocks by the plaster which 15 is subsequently applied.

My invention can be readily understood from the accompanying drawings which illustrate an embodiment thereof. In these drawings, Fig. 1 shows my invention as applied to blocks made of fibrous material; Fig. 2 shows the invention as applied to gypsum blocks with the clips applied in a slightly different manner to connect the first and second tiers; Fig. 3 is an enlarged section on 25 line 3—3 of Fig. 1, and Fig. 4 is an enlarged perspective view of one of the clips which I use.

First considering Fig. 4, the clip, which as an entirety is designated by the letter A, 30 comprises two end portions 2 and 4 which are of similar shape, and a central portion 6 which connects the end portions. The central portion 6 should be of a length just equal to the thickness of the blocks with 35 which the clip is to be used. It will be noted from Fig. 4 that the entire clip can be bent from a single piece of metal. Cross member 6 preferably connects the two ends 2 and 4 at the centers of these two ends. In each 40 end portion 2 and 4 are a series of holes 8 which serve to lock the clips to the blocks when the plaster is applied.

In Fig. 1, I have designated the fibrous blocks by the letter F, and in Fig. 2 I have 45 designated the gypsum blocks by the letter G.

In building a wall such as is shown in Fig. 1, the first course of blocks is laid up on their side with the ends touching. Clips A are then driven down between adjoining blocks 50 so that the end portions overlie the ends of two adjacent blocks, and the central portion 6 just drops down below the upper edge of the blocks, lying between them. The second course of blocks is then laid in place in staggered relation to the first course and these blocks are pushed down between the upper

parts of end portions 2 and 4 of the clips A. At the same time, as soon as a block F of the second course is put in place, a clip A is pushed into position so that the lower portions of ends 2 and 4 embrace a lower block F and the central portion 6 lies against the end of the second tier block F. The next block is then forced into this clip so that it likewise is held by the upper portion of ends 65 2 and 4. The wall is laid in this same manner up to the top.

In Fig. 2 the method of laying up the wall is exactly the same as that described in connection with Fig. 1, except that the clips A 70 are applied horizontally to the top of the first tier of blocks as is clearly illustrated. The rest of the wall may be laid up in the manner already described, or both the horizontal and vertical clips may be used.

A wall laid up in the ways described will be amply rigid so that it can be trued and will hold in place. It will not, however, ordinarily be sufficiently strong to stand regular use. It is intended that this wall 80 shall be plastered, preferably on both sides. When the plaster is applied it will go through the openings 8 in the clips and bind to the faces of the blocks G or F. When fibrous blocks such as are shown in Fig. 1 85 are used, the plaster will make a particularly strong connection with the blocks by entering the interstices between the fibres. Once the plaster is applied and sets, the clips will be rigidly locked to the blocks and the wall cannot be bent without shearing the joint between the plaster and the blocks, which is a stronger union than that ordinarily made with mortar. By the arrangement shown a wall can be built very rapidly and inexpensively, and it has the further advantage that it can be plastered immediately without waiting for mortar to dry.

What I claim is:

1. In a wall structure made up of courses 100 of blocks laid in staggered relation, clips each having a central portion which extends between two adjacent blocks and having end portions connected with the central portion which end portions extend over parts 105 of the faces of at least three adjacent blocks comprised in the wall.

2. A wall structure comprising a series of blocks laid up with edges in contact and metallic clips holding said blocks together, 110 said clips having flat parallel end portions and a central connecting portion and so posi-

tioned that the end portions embrace between them parts of three blocks and the central portion lies between edges of the blocks.

3. A structure as defined in claim 2, further characterized by the fact that the end portions of the clips are perforated and the structure comprises a coat of plaster which locks the clips to the blocks.

4. A structure as defined in claim 2, in which the blocks are made of loosely compacted fibrous material, and the end portions of the clips are perforated, and the structure comprises a coat of plaster which extends

through the perforations in the ends of the clips and into the interstices between the fibres of the blocks, thereby securing the clips in place. 15

5. In combination, a building block, a clip embracing the block having a portion running between two faces of the block, and two flat portions adjacent such faces of the block, perforations in said flat portions, and plaster in said perforations locking said clip to said block. 20

JAMES MONROE HEWLETT.
